UNITED STATES PATENT OFFICE.

JOHN B. GOODWIN, OF PROVIDENCE, RHODE ISLAND, ASSIGNOR TO
WILLIAM P. GOODWIN, OF SAME PLACE.

FOLDING AND SWINGING GATE.

SPECIFICATION forming part of Letters Patent No. 381,064, dated April 10, 1888.

Application filed October 12, 1887. Serial No. 252,100. (No model.)

To all whom it may concern:

Be it known that I, JOHN B. GOODWIN, of Providence, in the county of Providence and State of Rhode Island, have invented certain new and useful Improvements in Folding and Swinging Gates, of which the following is a full, clear, and exact description, reference being had to the accompanying drawings, forming part of this specification.

10 This invention relates to a folding and swinging gate of the character shown and described in United States Letters Patent No. 369,284, granted to me August 30, 1887, and is an improvement upon the aforesaid patent, to which reference is hereby made for the more thorough understanding of this invention.

15 The objects of my invention are to facilitate the operations both of folding and extending the gate; to more securely brace the gate when extended, thereby rendering this class of gates quite rigid; to automatically lock the gate so as to prevent folding of the same, and to catch and hold the gate against lateral play when in extended position.

20 To the aforesaid purposes my invention, briefly stated, consists, essentially, in an operating-rod hinged by one end to the folding gate and pivoted by the other end to a traveler or slide moving on the vertical hinge-bar 25 of the gate; in the brace-bar pivoted to the operating-rod, and the slotted brace-links pivoted to the brace bar, and the hooked lugs on the uprights of the gate to receive the said links; in the latch device on the operating-rod for engaging one of the uprights of the 30 gate to lock the same, and in the two-way or double snap-latches for catching and holding the outer end of the gate to prevent lateral play or wabbling of the gate when extended.

35 In order that my invention may be fully understood, I have illustrated in the accompanying drawings the best forms thereof so far devised by me, with the knowledge that such forms admit of modification, without however 40 making a substantial departure from the spirit of my invention, as hereinafter described and claimed.

45 In the accompanying drawings, Figure 1 is a broadside view of my improved folding and swinging gate in extended position, and shown as mounted at one of the side entrances of the

platform of an ordinary railway-car, which is shown in portion. Fig. 2 is an enlarged detailed view, partly in full and in section, of part of my improved gate as hereinafter described; and Fig. 3 is a top plan view of the left-hand portion of Fig. 2. Fig. 4 is an enlarged detailed view of the double snap-latch used with the gate.

55 In the said drawings like numbers of reference designate corresponding parts throughout.

60 Referring to the drawings 9 is the car having the platform 10, across which the folding and swinging gate 11 is operated, the gate being composed of the lazy-tong projectors 13, which support and operate the uprights or palings 12. The gate turns on the hinge-bar 14, and is suspended from the connecting-rod 16, depending from the traveling hanger 17. 65 All the aforesaid parts are constructed and are designed to operate as described for the same in the above-referred to patent.

70 As part of the present invention I introduce the operating rod or lever 35, which is pivoted on the pin 36, fixed across the casing 37, which is secured upon the connecting-rod 16, which is formed with the vertical slot 38, (shown in Fig. 2,) for the rod 35 to move through. The other end of the operating-rod 35 is hinged by 75 the bolt 43 to the traveler or slide 39, which consists of two members secured together with the screw 40, and this traveler works up and down in the slot 41 in the hinge-bar 14. The traveller is provided with the rollers 42, 80 to lessen the friction in reciprocating. The handle 44 is formed integral with the bolt 43. It is evident that by grasping the handle 44 and moving it up and down, so as to reciprocate the slide 39 on its bearings, the gate will 85 be folded and extended alternately. To render the manipulation of the gate easier, I pivot the brace-rod 45 to near the center of the operating-rod 35, and pass the pin 46, attached to the lower end of the brace-rod, through the 90 slots 47, formed in corresponding ends of the brace-links 48 and 49, which are hinged by their other ends to the hinge-bar 14 and the connecting-rod 16, respectively. Near the 95 lower ends of the uprights 12, and in a horizontal line, are secured the hooked lugs 50, which receive and snugly hold the brace-links when

the latter are in the horizontal positions shown in Fig. 1. As the operating-rod 35 is moved upward by one end, the attached brace-bar 45 will be raised vertically, as shown at one point 5 of its movement by dotted lines in Fig. 1, and the links will be moved out of the hooks and drawn up at an angle toward each other, and will allow the gate to be folded. These several additional pieces—namely, the rod 35, the brace 45, and the links 48 and 49—make the gate more rigid and better able to resist pressure than the heretofore constructions.

The operating-rod 35 is recessed, as at 51, on the under side thereof, in order to receive 5 and hold the heads of the uprights 12. By virtue of this construction the rod 35 is made to act as a guard-rail and as a strengthening-piece for the gate when the latter is in extended position.

o The gate is locked automatically, so as to prevent the folding of the same, by means of the bolt 52, which is set in the socket 53, formed in the operating-rod 35. One end of this socket is temporarily closed by a screw 5 plug, 54, which is set therein after the main part of the latch and the spring 55 which actuates the latch are inserted in the socket. The thumb-piece of the bolt projects through an opening, 56, leading into the socket. The end 5 of the bolt 52 takes into the notch 57, formed in the upright 12, the entering of which into the recess 51 automatically snaps the bolt and locks the gate against folding, in an obvious manner. The gate can be readily unlocked by retracting the bolt 52 by hand and then manipulating the operating-rod 35, as before described.

To prevent lateral play or wobbling of the gate when extended as shown in Fig. 1, I provide 5 the double or two-way snap-latches 58, which consist each in the fixed plate 59, on which is pivoted a pair of oppositely-disposed latches or trips, 60, each having a spring, 61, tending to keep it pressed outward. These springs are set in sockets 62, drilled in the bed 5 on which the plate is mounted, the bed also being formed with a slit, 63, to receive the latches 60 when depressed. The latches 58 are placed in alignment with the gate, and are 5 fixed upon the side of the car, so as to receive and hold the outer upright, 12, in position. Should the gate when extended lie to either side of the latches, the gate may be readily snapped into position from either side and held against lateral movement by the latches 58.

Having thus described my invention, I claim as new and desire to secure by Letters Patent—

1. The combination, with a folding gate and the hinge-bar thereof, of the operating-rod hinged to the gate and connected movably to the hinge-bar, whereby the gate may be extended and folded by the movements of the operating-rod, as described.

5 2. The combination, as hereinbefore set forth, with a folding gate provided with the uprights,

of an operating-rod hinged to one of the uprights and provided with a locking device engaging one of the other uprights, whereby the gate may be securely locked against folding, 70 substantially as and for the purpose herein described.

3. The combination, as hereinbefore set forth, with a folding gate having the uprights, of an operating-rod recessed to receive the upper 75 ends of said uprights and hinged by one end to the gate, whereby the operating-rod may act as a brace for the uprights when the gate is extended, substantially as and for the purpose herein described.

80 4. The combination, as hereinbefore set forth, with a folding gate and an operating-rod hinged thereto and acting to extend and fold the gate by its movements, of the brace-links pivoted to the gate near the base thereof by their corresponding ends, and the pivoted brace-bar intermediate the said operating-rod and the other ends of the said links, substantially as and for the purpose herein described.

85 5. The combination, as hereinbefore set forth, with a folding gate having the uprights provided with the hooked lugs, of the operating-rod hinged to the gate, the brace-links pivoted by corresponding ends to the gate, near the base thereof, and adapted to engage with the 90 said lugs when the gate is extended, the brace-bar pivoted to the other ends of the brace-links and pivoted to the operating-rod, substantially as and for the purpose herein described.

95 100 6. The combination, as hereinbefore set forth, with the hinge-bar and the folding gate having the uprights, of the operating-rod hinged to the gate and having a movable or sliding connection with the hinge-bar, the brace-links pivoted by their corresponding ends to the uprights of the gate, and the brace-bar pivoted to the operating-rod and to the other ends of the brace-links, substantially as and for the purpose herein described.

105 110 7. The combination, as hereinbefore set forth, with the slotted hinge-bar and the folding gate having the uprights, of the traveler provided with rollers and mounted on the hinge-bar and taking through the slot thereof, the operating-rod hinged by one end to the gate and hinged by the other end to the traveler on the hinge-bar, and provided with a handle, substantially as and for the purpose herein described.

115 120 8. The combination, as hereinbefore set forth, with the folding gate having the uprights, one of which is notched, of the operating-rod recessed to receive the heads of the uprights and hinged to the gate, and provided with the 125 spring-acted bolt, which engages the notch of the said upright, substantially as and for the purpose herein described.

9. The combination, as hereinbefore set forth, with the folding gate, of the one or more stationary double snap-latches for engaging and holding the outer end of the gate when the 130

same is extended, substantially as and for the purpose herein described.

10. The combination, as hereinbefore set forth, with the folding gate 11, of the operating-rod 35, hinged by one end to the gate and acting to fold and extend the gate, as described.

11. The combination, as hereinbefore set forth, with the hinge-bar 14 and the folding gate 11, of the operating-rod 35, hinged by one end to the gate and movably connected by the other end to the hinge-bar 14, substantially as and for the purpose herein described.

12. The combination, as hereinbefore set forth, with the hinge-bar 14, formed with slot 41, and the folding gate 11, attached to the bar and the connecting-rod 16, of the operating-rod 35, pivoted to the rod 16, the slide or traveler 39, mounted on the hinge-bar 14, and the rod 35, hinged thereto, the brace-bar 45, pivoted to the rod 35, and the slotted brace-rods 48 and 49, hinged to the hinge-bar 14 and the connecting-rod 16, respectively, and hinged to the brace-bar 45, substantially as described.

13. The combination, as hereinbefore set forth, with the folding gate 11, having the uprights 12, provided with the hooked lugs 50,

of the operating-rod 35, hinged to the gate, and the slotted brace-links 48 and 49, the brace-bar 45, intermediate the rod 35 and the said links, substantially as described.

14. The combination, as hereinbefore set forth, with the hinge-bar 14, formed with slot 41, and the gate 11, having the connecting-rod 16, of the slide or traveler 39, working on the hinge-bar, the operating-rod 35, hinged to rod 16 and pivoted to the slide 39, and provided with the handle 44, and formed with the recesses 51, the brace-links 48 and 49, and the brace-bar 45, intermediate the links and the brace-rod, as described.

15. The combination, with the gate 11, having the uprights 12, one of which is notched at 57, of the operating-rod 35, formed with the socket 53 and opening 56, and the spring-acted bolt 52, for engaging the notch 57 of the upright, as described.

16. The combination, as hereinbefore set forth, with the folding gate 11, of the two-way snap-latches 58, for preventing lateral play of the gate when extended as described.

JOHN B. GOODWIN.
